UNITED STATES PATENT OFFICE.

WARREN M. BRINKERHOFF, OF AUBURN, NEW YORK.

DESIGN FOR A SECTION-KNIFE FOR MOWING-MACHINES.

SPECIFICATION forming part of Design No. 28,456, dated April 5, 1898.

Application filed March 3, 1897. Serial No. 625,900. Term of patent 14 years.

To all whom it may concern:

Be it known that I, WARREN M. BRINKERHOFF, a citizen of the United States, residing at Auburn, in the county of Cayuga and State of New York, have invented and produced a new and original Design for a Section-Knife for Mowing-Machines; and I do hereby declare the following to be a full, clear, and exact description of the same, reference being had to the accompanying drawings, forming a part thereof.

My new and original design is illustrated in the accompanying drawings, in which—

Figure 1 represents a plan view of a section-knife embodying my design, and Fig. 2 is a section-knife on line 2 2 of Fig. 1.

According to my design the section is formed with a butt or edge *a*, having at each side vertical edges *b b*, said edges *b b* being connected

with butt or edge *a* by downwardly-extending inclined edges *c c*. Adjacent to the front end of edges *b b* inclined edges *d d* extend to the front end *e* of the knife. The inclined edges *d d* are beveled, as shown at *ff*. The section is also provided with two apertures *g g*, which are located adjacent to the butt or edge *a*.

What I claim, and desire to secure by Letters Patent, is—

The design for a section-knife for mowing-machines, substantially as herein shown and described.

In testimony whereof I have affixed my signature in presence of two witnesses.

WARREN M. BRINKERHOFF.
